UNITED STATES PATENT OFFICE.

DAVIESS B. WHITELY, OF WHITESVILLE, KENTUCKY.

FOLDING ROCKING-CHAIR.

SPECIFICATION forming part of Letters Patent No. 633,677, dated September 26, 1899.

Application filed May 14, 1897. Serial No. 636,505. (No model.)

To all whom it may concern:

Be it known that I, DAVIESS B. WHITELY, of Whitesville, in the county of Daviess and State of Kentucky, have invented certain new and useful Improvements in Folding Rocking-Chairs; and I do hereby declare the following to be a full, clear, and exact description of the invention, such as will enable others skilled in the art to which it appertains to make and use the same.

This invention relates to an adjustable folding rocking-chair adapted for use in different places and for different purposes; and it consists, essentially, of a specific form of slotted and adjustable frame, movable supports, braces, and intermediate connections.

The invention further consists of the details of construction and arrangement of the several parts, which will be more fully hereinafter described and claimed.

The object of the invention is to increase the facility with which a rocking-chair can be adjusted to incline at different angles and still preserve its rocking action, the parts being simple and effective in their construction and operation, strong and durable, and readily adjusted.

In the accompanying drawings, Figure 1 is a perspective view of a rocking-chair embodying the invention. Fig. 2 is a longitudinal vertical section of the same on the line *x x*, Fig. 1. Fig. 3 is a detail perspective view of a part of the chair. Fig. 4 is a side elevation of a modified form of construction, showing the seat and back formed by a continuous web. Fig. 5 is a detail perspective view of the rear portion of a chair, showing a further modification. Fig. 6 is a perspective view of a further modification of the chair.

Referring to the drawings, wherein similar numerals of reference are employed to indicate corresponding parts in the several views, the numeral 1, Figs. 1 and 2, designates rockers of any preferred form of construction and having pivotally attached thereto the opposite bars 2 of an adjustable frame 3. The rear ends of the said bars 2 are removably attached to the inner sides of the rear portions of the rockers 1 by a round 4, and at their front ends the bars 2 are connected to each other by a round 5. The rear portions of the said bars 2 are formed with transverse slots 6 in their upper edges, arranged at a slight an-

gle of inclination, and the under sides of the front portions thereof have notches 7 therein and pins 8, projecting inwardly therefrom, adjacent to the said notches 7. At the front of the chair are a pair of supports 9, connected to the inner sides of the front end of the rockers by a round 10 and of themselves attached to each other by a brace-round 11. As shown in Fig. 3, the supports 9 have at their outer ends outwardly-extending upwardly-projecting keepers 12, which bear against the outer sides of the bars 2 to retain the upper ends 65 of the said supports in engagement with the notches 7, and to the inner sides of the said supports catches 13 are movably connected and are adapted to engage the inwardly-extending pins 8 on the said bars 2 to lock the 70 said supports in their adjusted position. To the bars 2, near their front ends, are attached the lower ends of arm-supports 14, and on the upper ends thereof are movably-supported arm-rests 15, having broad pieces or strips 16, 75 secured on the upper edges thereof to provide extended surfaces. The rear ends of the arm-rests are attached to the side bars 17 of a back 18, the lower ends of said bars being also movably secured to the bars 2 of the frame 3 and of 80 themselves attached to each other by cross-slats 19 at the upper and lower portions thereof, with an intermediate upholstering or other covering 20. To the said side bars 17 of the back and above the points where the arm-rests 15 are attached brace-arms 21 are movably secured and are connected at their lower ends by a round 22, which is adapted to engage the slots 6 in the side bars 2 of the frame 3 to hold the back in adjusted position at varying angles and in accordance with the said 85 slots 6 engaged by the said round 22. The seat in this form of device is supported by the round 5, connecting the front ends of the said bars 2 of the frame 3, and comprises oppositely-disposed side bars 23 and end bars 24, let into the said side bars, and from the rear end bar extends a web 25, running up to the lower slat 19 of the back 18 to support the lower portion of the back between the slat 100 and the seat. The said back and seat can be suitably upholstered or cushioned and form a convenient and comfortable rest and permit the occupant to recline.

If the parts of the chair are adjusted sufficiently to lower the back, a couch or bed-chair

is provided, and all the parts being pivotally attached the supports 9 and braces 21 when disconnected permit the several parts to be folded in compact form.

5 In Fig. 4 a slight modification of the construction is shown, and therein the seat and back are connected to each other and the said seat supported by means of a back web 26. The holding devices of the rear surface of the 10 bar in this instance are also modified and consist of plates carrying forwardly-projecting hooks to engage the lower portion of the brace-arms 21.

In Fig. 5 a still further modification is 15 shown, and in this instance the side bars 27 of the back have enlargements or ears 28 projecting rearwardly, to which a pair of yoked arms 29 are movably attached and converge at their lower ends and connected by cross- 20 pins 30. The frame 3 in this instance is also supplied with a central rack-bar 31, located at the rear and supported by flat cross-bars 32, the said rack-bar taking the place of the slots 6 in the side bars 2 in the construction 25 heretofore set forth. This rack-bar extends longitudinally of the chair, and in operation the lower pin 30 of the yoke-arms 29 engages the rack-bar to support the back of the chair at varying elevations. The flat cross-bars 32 30 hold the rack-bar 31 rigidly and against movement, and in other respects this form of chair will be the same as that shown by Fig. 1.

In Fig. 6 the bars 2 have their front ends resting on a cross-rod 33, mounted in the supports 9. The said supports 9 are hinged at their lower ends to the rockers 1 and connected by a loose joint at their upper ends to the arm-rests 15. The said arm-rests are extended at the rear and have the brace-arms 40 21 secured directly thereto. In this instance also the arms are slotted, as at 34, and therein extend pins 35, projecting from the sides of the back, and are held in place by catches 35^a, secured to the arm-rests and adapted to turn 45 over said slots. The inner sides of the supports 9 have cam-buttons 36 attached thereto to hold the front ends of the bars 2 depressed. The bars 2 in this instance are also slotted at the rear, and the arms 21 have a lower round 50 22 to engage said bars. In this form of the device the seat will be automatically adjusted with the back. The said seat and back are not shown in this figure, but will consist, preferably, of a continuous web of material, which 55 will be adjusted by the movements of the parts to which it is attached.

The chair as thus described can be ornamented and constructed of any suitable material—either entirely of wood or a composition of wood and metal, as found desirable.

A suitable foot-rest is also intended to be attached to the front portion of the chair, and this may be of any preferred or well-known form of construction.

65 It is obviously apparent that many minor changes in the details of construction and the arrangement of the several parts might

be made and substituted for those shown and described without in the least departing from the nature or spirit of the invention.

Having thus described the invention, what is claimed as new is—

1. In a chair, the combination of rockers, a frame movably attached thereto provided with slots and notches, a back having supports adjustably engaging the rear of the said frame, supports attached to the front parts of the rockers and engaging the front of said frame, pins projecting inwardly from the front portion of the frame, catches carried by the 80 said supports to engage said pins, and a seat and arms, substantially as and for the purposes specified.

2. In a chair of the character set forth, the combination of a seat, a frame having front 85 and rear engaging devices, a pair of rockers to which the said frame is movably attached, supports movably connected to the front portion of the rockers and adjustably engaging the opposite front portions of the said frame, 90 a back having side bars movably attached to the said frame, and arm-rests movably connected to the said frame and side bars of the back, substantially as and for the purposes specified.

3. In a chair, the combination of a pair of rockers, a frame movably attached to the rear of said rockers, supports adjustably connected to the front of the rockers and movably engaging the front portion of said frame, a seat 100 and back attached to said frame, arm-rests movably attached to the frame and back, and an adjustable support movably depending from the back and adapted to engage the rear portion of the frame, substantially as and for 105 the purposes specified.

4. In a chair, the combination of a pair of rockers, a frame pivotally attached to the rear portion thereof and consisting of opposite side bars connected at rear and front by rounds 110 and having slots in the rear upper edges and notches in the front lower edges, supports attached to the front ends of the rockers by a round extending from one to the other and having their upper ends movably engaging the notches in the lower front portion of the said side bars, pins extending inwardly from the front portions of said side bars, catches 115 movably attached to the said supports and engaging the said pins, a seat and back movably secured to the said frame, arm-rests adjustably attached to the said frame and back, and an adjustable support depending from the rear of the back to movably engage the rear slots of the said frame, substantially as 120 and for the purposes specified.

In testimony whereof I have signed this specification in the presence of two subscribing witnesses.
